ABSTRACT

A low profile rail mounting system, comprises an adaptor for mounting an accessory on a firearm rail. The adaptor can include flexible material such that the adaptor can be snapped into position to mount the adaptor on the firearm rail. The adaptor includes opposite grooves that receive the firearm rail to maintain the adaptor on the rail.

LOW PROFILE RAIL MOUNT FOR FIREARM

CROSS-REFERENCE TO RELATED APPLICATIONS

This application is a divisional of and claims priority to U.S. application Ser. No. 17/032,493, filed Sep. 25, 2020, which claims the benefit of U.S. Provisional Application No. 62/905,902, filed Sep. 25, 2019, the entireties of which are hereby incorporated by reference.

FIELD

The present disclosure generally relates to mounting hardware for attaching an accessory to a firearm rail, such as a Picatinny® or M-Lok® rail, and in particular, a low profile mounting system that reduces bulk when mounting an accessory to a firearm.

BACKGROUND

Rail systems on firearms are mounting brackets (usually made of strips of metal or polymer) on the gun's receiver, handguard, or fore-end stock to allow attachment of accessories such as optical sights, tactical lights, laser sight and the like. Rail systems usually are based on the handguard of a weapon and/or the upper receiver. Common types of rail systems for firearms are the dovetail rail, the Weaver rail, the Picatinny® rail (also known as the MIL-STD-1913 or STANAG 2324 rail), and the Magpul M-Lok®. One of the problems with mounting to rail systems is that the mounting hardware creates added bulk.

SUMMARY

In one aspect, a low profile rail mounting system comprises an adaptor comprising flexible material permitting the adaptor to be snapped into position to mount the adaptor on a firearm rail. The adaptor includes an upper adaptor section configured to seat on the firearm rail. The adaptor includes a first wing section and a second wing section each extending distally from opposite sides of the upper adaptor section and extending over the firearm rail when mounted. The adaptor includes a first foot section and a second foot section on a distal end of the respective first wing section and second wing section. The first foot section and first wing section form a first groove, and the second foot section and second wing section form a second groove to secure the adaptor to the firearm rail when mounted.

Other objects and features of the present disclosure will be in part apparent and in part pointed out herein.

BRIEF DESCRIPTION OF THE DRAWINGS

FIG. 1 is a top perspective of a low profile rail mounting system;

FIG. 2 is a bottom perspective of the low profile rail mounting system shown in FIG. 1;

FIG. 3 is a top front perspective of a low profile rail mounting system, an accessory, and a Picatinny® rail;

FIG. 4 is a cross-sectional top perspective of a low profile rail mounting system mounted to a Picatinny® rail;

FIG. 5 is a cross-sectional view of a low profile rail mounting system and accessory mounted to a Picatinny® rail; and

FIGS. 6A-6C show a laser sight accessory and a low profile rail mounting system;

Corresponding reference characters indicate corresponding parts throughout the drawings.

5

DETAILED DESCRIPTION

Disclosed herein is a low profile rail mounting system for mounting to a firearm rail, such as a Picatinny® or M-Lok® rail. The disclosed low profile rail mounting system allows for easy mounting of firearm accessories, such as scopes, laser sites, and the like, to the rail and hence the firearm to which the rail mounting system is attached. The low profile rail mounting system includes an adaptor (e.g., adaptor plate) that comprises a flexible material permitting the adaptor to be snapped into position. For example, the flexible material may include plastic, fiber reinforced plastic, fiber reinforced polymer, and/or polymer material. The adaptor may be composed entirely of the flexible material. 10 Alternatively, the adaptor may include non-flexible material in combination with the flexible material (e.g., providing relatively rigid portions and relatively flexible portions). The adaptor includes an upper section configured to seat on a firearm rail, making contact with the upper or top surface(s) of the rail. For example, the adaptor can straddle the rail transverse to the long axis (longitudinal axis) of the rail or firearm. The adaptor extends longitudinally along the top of the rail, for example over one or more cross slots of the firearm rail. The adaptor plate includes a first wing section 15 and a second wing section each extending distally from opposite sides of the upper section and extending over and at least partially encircling the sides of the firearm rail when mounted. Foot sections are connected to respective wing sections. The first foot section and first wing section form a first groove (e.g., v-groove) on what would be considered the interior of the adaptor. The second wing section forms a second groove (e.g., v-groove) opposite the first groove on the interior of the adaptor. The first groove and the second groove work together on opposite sides of the rail system to 20 secure the adaptor to the firearm rail when mounted thereon, for example, by capturing the respective sides of the rail. The sides of the rail may be triangular portions of the rail that protrude laterally. The adaptor plate includes one or more risers on the upper section, for example, to place an accessory at a proper height relative to the rail, barrel, and/or receiver of the firearm. The adaptor includes one or more alignment bosses on a bottom surface of the upper section (considered the inside of the adaptor plate) that are configured to align with and be received in cross slots on the 25 firearm rail when mounted. The alignment bosses work to align the adaptor and hence the accessory longitudinally with respect to the rail and/or firearm. The adaptor first foot section and second foot section each include a tapered section opposite the grooves. The tapered sections are configured to provide an interference taper fit between the adaptor and firearm accessory such that when the adaptor and the firearm accessory are connected, the grooves are biased inward to provide lateral clamping force between the 30 firearm accessory and the firearm rail. Desirably, the adaptor protrudes less than $\frac{3}{4}$ inch, more desirably less than $\frac{5}{8}$ inch, and more desirably less than $\frac{1}{2}$ inch, from a surface of the rail on which the upper section is seated when installed.

The low profile rail mounting system can include one or more fasteners, such as screws, bolts and the like, that can secure a firearm accessory to the adaptor, for example when mounted to the rail system. The one or more fasteners can further secure the adaptor to the firearm rail when mounted.

In some examples, the one or more fasteners are of sufficient length to extend through both the accessory and the adaptor plate to secure both the accessory and the adaptor plate to the firearm rail. The low profile rail mounting system further includes one or more nuts, such as t-nuts, to secure the one or more fasteners that are secured to the underside of the adaptor.

The low profile rail mounting system can include a firearm accessory, such as laser site, and/or a scope. The low profile rail mounting system can include a rail system, such as a Picatinny® rail system or a M-Lok® rail system.

Referring now to FIGS. 1-6, a low profile rail mounting system 10 includes an adaptor 20, fasteners 40, and T-nuts 50. The adaptor 20 (e.g., “adaptor plate”) includes an upper section 22, a first wing section 24a, and a second wing section 24b that extend from the upper section 22, for example to at least partially envelop a portion of the rail. The adaptor 20 can further include risers 34a and 34b which include openings 36 to accommodate fasteners 40. The adaptor 20 further includes a first foot section 30a and a second foot section 30b on the distal ends of the respective first wing section 24a and second wing section 24b. Together, the first foot section 30a and first wing section 24a form a first groove 28a (e.g., “v-groove”), and the second foot section 30b and second wing section 24b form a second groove 28b (e.g., “v-groove”) to secure the adaptor 20 to a firearm rail. For example, the adaptor may clamp or pinch the rail between the two grooves 28a and 28b.

With reference to FIG. 2, the adaptor 20 can further include alignment bosses 26 on a lower surface of the upper section 22. The alignment bosses 26 are spaced and configured to align with and be received in cross slots of the firearm rail when mounted.

Turning to FIG. 3, the relative positions of the adaptor 20, the fasteners 40, an accessory 60, in this case a laser sight, and a Picatinny® rail 90 situated on a hand guard 80 are depicted prior to assembly. As shown, the adaptor 20 snaps over the a Picatinny® rail 90, where it forms a snap fit and can be secured, along with the accessory 60, by the fasteners 40.

Turing to FIG. 4, a cross-sectional top perspective of the adaptor 20 mounted to a Picatinny® rail 90 is shown to illustrate how the adaptor 20 couples to the Picatinny® rail 90. As seen in FIG. 4, the first groove 28a and the second groove 28b dove tail to the protruding sides 94a and 94b of the Picatinny® rail 90. As the adaptor 20 snaps over the a Picatinny® rail 90, the first groove 28a and the second groove 28b act together to secure the adaptor 20 in place, for example as a snap- or pinch-fit, on the Picatinny® rail 90. Also, as seen in FIG. 4, the alignment bosses 26 on the bottom surface of the upper section 22 protrude into the cross slots 92 of the Picatinny® rail 90. This nesting of the alignment bosses 26 within the cross slots 92 limits the adaptor 20 from moving axially along the Picatinny® rail 90.

Turning to FIG. 5, a cross-sectional view of the adaptor 20 and an accessory 60 is shown mounted to a Picatinny® rail 90 system with fasteners 40 and t-nuts 50. This view shows how the components of the low profile rail mount system work together to secure the adaptor 20 and the accessory 60 to the Picatinny® rail 90. As the t-nut 50 is drawn up (see arrows A) by tightening of the fasteners 40, the accessory 60 is drawn down, relative to the adaptor 20. As the accessory 60 is drawn down, it pushes on taper 31 of the first foot section 30a and the second foot section 30b causing the first wing section 24a and the second wing section 24b to clamp to the Picatinny® rail 90 with the first groove 28a and the

second groove 28b. This interference taper fit between the adapter 20 and the accessory 60 is such that when the fasteners 40 are torqued in place, the grooves 28a and 28b on the adapter 20 are biased inward (see arrows B) providing lateral clamping force between the adaptor 20 (and thus the accessory 60) and the Picatinny® rail 90.

FIGS. 6A-6C illustrate an accessory system 60 and the low profile rail mounting system 10. In the illustrated embodiment, the accessory system 60 includes an accessory 60A and an associated remote switch 60B. For example, the accessory 60A can include a laser 100 (broadly, “sight”) and/or a light 102. In the illustrated embodiment, the accessory 60A includes a laser 100 and a light 102 with a shared housing that is mountable to a firearm rail using the adaptor 20. The remote switch 60B includes a mount 110 having a similar construction as the adaptor 20 (e.g., wings, feet, flexible material) enabling the remote switch to be mounted to the firearm rail system (e.g., on same or different rail as the accessory 60A) in a similar snap-on manner. The remote switch 60B includes an actuator 112 (e.g., push-button switch and/or momentary switch) for actuating the accessory 60A (e.g., on, off, different modes, etc.). The remote switch 60B can be tethered to the accessory by connecting a tether 120 to the accessory 60A (e.g., plugging a male connector into a port on the accessory). In some circumstances, the remote switch 60B may not be used. Whether the remote switch is used or not, the accessory 60A can be actuated using one or more actuators (e.g., rotary dial 126) on the accessory. It will be appreciated that the light 102 and laser 100 are provided in a side-by-side arrangement to provide a low profile fit on the firearm. The housing of the accessory 60A straddles the adaptor 20, with the light 102 and laser 100 on opposite sides of the adaptor. The housing of the accessory 60A includes a portion between the light 102 and laser 100 to which the adaptor is connected via the fasteners 40. In particular, the intermediate portion of the housing includes openings 130 through which the fasteners 40 extend. The risers 34a, 34b of the adaptor 20 are received in a recess on the bottom of the accessory 60A. The arrangement is such that the light 102 and laser 100 are positioned to opposite sides of the rail and/or straddle the rail to which the adaptor 20 is mounted. To install the accessory 60A on the rail, the accessory and adaptor 20 can be loosely connected by the fasteners 40. Then the adaptor 20 is snapped onto the rail, and the fasteners 40 are tightened to draw the nuts 50 toward the adaptor. The tightened fasteners 40, the clamping of the adaptor 20 on the rail, and the bosses 34a, 34b in the rail, serve to secure the adaptor and thus the accessory in position on the rail.

It will be apparent that modifications and variations are possible without departing from the scope of the invention defined in the appended claims.

As various changes could be made in the above constructions and methods without departing from the scope of the invention, it is intended that all matter contained in the above description and shown in the accompanying drawings shall be interpreted as illustrative and not in a limiting sense.

What is claimed is:

1. A low profile mounting system for mounting on a firearm component, the system comprising:
a nut; and
an adaptor mountable on the firearm component, the adaptor comprising:
an upper adaptor section;
a first foot section supported by the upper adaptor section;

a second foot section supported by the upper adaptor section, the first foot section and the second foot section being configured to snap the adaptor on onto the firearm component with the first and second foot sections in mounting engagement with the firearm component; and

an accessory mount for connecting an accessory to the adaptor via the nut, the accessory mount including a nut holder configured to limit rotation of the nut.

2. The system of claim 1, wherein the adaptor comprises flexible material configured to permit the first and second foot sections to snap the adaptor onto the firearm component.

3. The system of claim 2, wherein at least one of the first or second foot sections has an at rest position and the flexible material is configured to permit said at least one foot section to deflect away from the at rest position and to resiliently return toward the at rest position to provide a snap connection to the firearm component.

4. The system of claim 1, wherein the adaptor is formed from a single piece of material.

5. The system of claim 1, wherein the upper adaptor section, the first foot section, and the second foot section are integrally formed as a unitary piece of material.

6. The system of claim 1, further comprising at least one alignment boss configured to be received in a slot of the firearm component, the at least one alignment boss extending downwardly from the upper adaptor section and being fixed in position with respect to the upper adaptor section.

7. The system of claim 1, further comprising at least one alignment boss configured to be received in a slot of the firearm component, the at least one alignment boss extending downwardly from the upper adaptor section, the alignment boss and upper adaptor section being integrally formed as a unitary piece of material.

8. The system of claim 1, wherein the nut comprises a t-nut.

9. The system of claim 1, wherein the accessory mount is supported by the upper adaptor section.

10. The system of claim 9, wherein the accessory mount extends upwardly from the upper adaptor section.

11. The system of claim 1, wherein the nut holder includes a recess configured to receive the nut.

12. The system of claim 11, wherein the accessory mount includes an opening extending from the recess.

13. The system of claim 12, further comprising a fastener sized and shaped to be receive through the opening in the accessory mount and coupled to the nut to connect the accessory to the adaptor.

14. The system of claim 1, wherein the accessory mount includes an opening, and wherein the system further comprises a fastener sized and shaped to be receive through the opening in the accessory mount and coupled to the nut to connect the accessory to the adaptor.

15. The system of claim 1, wherein the adaptor includes first and second grooves configured to receive the firearm component to mount the adaptor on the firearm component.

16. The system of claim 15, wherein the first foot section borders the first groove and the second foot section borders the second groove.

17. The system of claim 1, wherein the adaptor is configured to provide an interference fit between the adaptor and the accessory such that when the adaptor is mounted on the firearm component, the first and second foot sections are biased inward to provide lateral clamping force on the firearm component.

18. The system of claim 1, wherein the first foot section includes a taper shaped and arranged on the adaptor to be engaged by the accessory to drive the first foot section toward the second foot section to further secure the adaptor to the firearm component when the adaptor and accessory are mounted on the firearm component.

19. The system of claim 1, wherein the first and second foot sections are arranged on the adaptor to be engaged by the accessory to bias the first and second foot sections toward one another to further secure the adaptor to the firearm component when the adaptor and accessory are mounted on the firearm component.

20. The system of claim 1, wherein the nut is a first nut, the accessory mount is a first accessory mount, and the nut holder is a first nut holder, wherein the system further comprises a second nut, wherein the adaptor comprises a second accessory mount for connecting the accessory to the adaptor via the second nut, the second accessory mount including a second nut holder configured to limit rotation of the second nut.
